UNITED STATES PATENT OFFICE.

GEORGE MALLORY, OF WATERTOWN, CONNECTICUT.

HOOP-SKIRT.

Specification forming part of Letters Patent No. 21,839, dated October 19, 1858; Reissued February 18, 1862, No. 1,276.

To all whom it may concern:

Be it known that I, GEORGE MALLORY, of Watertown, in the county of Litchfield and State of Connecticut, have invented a new 5 and useful Improvement in Ladies' Hooped Skirts; and I do hereby declare that the following is a full, clear, and exact description of the same, reference being had to the accompanying drawings, forming part of 10 this specification, in which—

Figure 1 is a side view of a skirt with my improvement, representing it as it appears when the wearer stands up. Fig. 2 is a side view exhibiting it as it appears when the 15 wearer sits down. Fig. 3 is a plan of one of the hoops.

Similar letters of reference indicate corresponding parts in the several figures.

This invention is intended to remedy a 20 great defect which exists in all the skirts heretofore manufactured with hoops or springs of metal. Owing to the inflexibility of such hoops or springs in an upward and downward direction, the fronts of those 25 whose back parts are sat upon, when the wearer sits down, are thrown upward and caused to raise the front of the dress in an objectionable manner.

My invention consists in constructing one 30 or more of the hoops or springs of a skirt in such a manner as to preserve as far as necessary its inflexibility in an upward and downward direction in all parts except at a convenient point or part on each side 35 where I make them flexible in such direction in order that they may bend and allow the front portion to hang down over the front of the seat when the wearer is sitting down.

40 A, A, A', A', B, B, are the hoops or springs of the skirt, and C, C, the connecting or suspending tapes. The lower hoops or springs A, A, and the upper ones B, B, are or may be of ordinary construction, that 45 is to say, of thin strips of steel, which, when bent into form and in place in the skirt, have their width in a vertical direction and are elastic in a horizontal direction. Those A', A', which are likely to be sat upon are

50 made in the same way, except that at each side a short piece is cut out or omitted and

the space filled by two pieces a, a, of the same or substantially similar material—preferably pieces of well-tempered thin flat steel spring—set with its edges transverse 55 to the edges of the other parts or with its width in a horizontal direction. These pieces a, a, are represented as being united with the other parts of the hoops by the ends of said pieces and those of the other 60 parts being inserted in slits cut transversely to each other in opposite ends of small blocks b, b, and soldered therein. This I consider to be the best method of construction, but a cheaper method of making them would be to twist a portion on each side of each hoop or spring A', to the 65 same position as a, a, relatively to the remainder of it. This I regard as equivalent to the first described method. Either of the 70 said methods will enable the hoops or springs to retain their circular form and leave them as inflexible in upward and downward directions as ordinary hoops, at all parts but at a, a, where they are capable 75 in a full-sized skirt of being bent as shown in Fig. 2, by the weight of the front part to allow the latter to fall down over the edge of a seat when the back part of the hoop is secured to the seat by being sat upon, or if 80 the weight of the skirt alone should not be sufficient, the weight of the dress outside of it could not fail thus to bend them. When the wearer stands up again the hoop resumes 85 its proper shape and horizontal condition.

What I claim as my invention, and desire to secure by Letters Patent, is:

The construction of one or more of the hoops or springs A', A', of a skirt with elastic pieces a, a, or their equivalent, arranged one on each side so as to provide for flexure of said hoop or hoops over the edge of a seat when its or their back parts are sat upon, without impairing the inflexibility 90 in an upward and downward direction of 95 any other parts than those where the flexure is immediately required, substantially as herein described.

GEORGE MALLORY.
